UNITED STATES PATENT OFFICE.

NATHANIEL G. WARTH, OF GALLIPOLIS, OHIO.

MUFFLER FOR AUTOMOTIVE ENGINES.

Application filed July 5, 1922. Serial No. 572,801.

To all whom it may concern:

Be it known that I, NATHANIEL G. WARTH, a citizen of the United States, residing at Gallipolis, in the county of Gallia and State of Ohio, have invented a certain new and useful Improvement in Mufflers for Automotive Engines, of which the following is a specification.

The objection to mufflers for motor vehicles as now commonly constructed and used is that by their frictional resistance they create back pressure against the piston of the engine during the exhaust stroke that interferes with the efficiency of the engine, 10 the discharge of the exhaust gases being incomplete and causing a mixture of burnt gas with the succeeding explosive charge. This trouble is accentuated by the inevitable accumulation in course of time of carbon 15 deposits in the muffler and its connections. The aim of my invention is to relieve to a large extent, if not entirely, the cause of these troubles.

The invention is embodied in the example 20 herein shown and described which I now regard as the preferred form of the invention, the features of novelty being finally claimed.

In the accompanying drawing—

Figure 1 is a view in end elevation showing a muffler with my invention embodied 25 therein.

Fig. 2 is a vertical central longitudinal sectional view of Fig. 1.

Fig. 3 is an elevation of the discharge 30 or rear end of the muffler.

Fig. 4 is an elevation of the front end of the muffler.

Fig. 5 is a detail in elevation of the centrally perforated baffle, and

Fig. 6 is a similar view of the annularly 40 perforated baffle.

The muffler body is composed according to a well known form of a series of cylindrical sections 7 and 8 all arranged alternately and each having a rabbet-like flange at one end and a diaphragm at its other end, the diaphragm of one set perforated centrally as shown at 7^a and the other perforated in a circle near its rim with a series of holes 8^a. The central openings 7^a stand opposite the solid portions within the annular series of perforations 8^a so that, as well understood, the gases pass obstructedly and generally in waved lines through the muffler as suggested by the ar-

rows in Fig. 2. The assembly of sections is provided at its rear end with a closing head 9 having an eccentric discharge pipe 9^a while the forward end is provided with a head 10 having a central opening from 60 which projects forwardly a flared or funnel shaped air collecting member 11. The funnel is provided with an inwardly extending stem 12 directed toward the central opening of the first or adjacent baffle 7. Centrally secured by means of a spider 13 in said head is a tube or pipe 14 for connection at its forward end to the discharge end of a pipe leading from the exhaust manifold of the engine. The two heads 9 and 10 are 65 connected by means of several long bolts 14^a passing through the baffle, suitable nuts or other fastenings for the bolts being provided to secure the heads and sections in assembled relation as shown. The muffler as 70 thus constructed is mounted upon the motor vehicle in the usual position.

In operation the impulses of the burnt gases enter the muffler through the pipe 14 and are projected through the tapered stem 80 12 into the first chamber and in this passage the gases are accompanied by a large volume of cooling atmospheric air from the funnel entrained by the suction due to the velocity of the entering gases. This forwardly flared or funnel shaped member 11 insures the continuous collection and concentration into the muffler of a large volume of cooling air especially when the vehicle is in forward motion, the entrance of cooling air being increased in volume by the powerful impulses 85 of the exhausting gases. These impulses also bring about a desirable and timely admixture of the cooling air with the gases. The continuous entrance and passage of atmospheric air into and through the muffler 90 insures the cooling and scavenging of the muffler, especially between impulses of the exhaust. The admixture and circulation of the cooling air at substantially atmospheric 100 pressure with the hot gases in the muffler also cause a decided reduction in the temperature of the gases and consequently of their volume and pressure from what they would normally be in the usual muffler 105 thereby promoting the discharge of the exhaust from the manifold which thus takes place at nearly atmospheric pressure thereby reducing discharge noises. The avoidance of back pressure as effected by my construction 110

2
also, as before indicated, prevents to a large extent, the admixture of exhaust gases with the explosive fuel in the cylinders of the engine and a consequent better scavenging of the cylinders and manifold. A further advantage of the construction is that in case of back firing within the muffler the explosion is vented at the forward end in addition to the usual venting at the rear end.

5 The forms and arrangement of the parts can be varied without departing from the gist of the invention claimed, for example the funnel may be entirely located within 15 the forward section of the muffler body.

What I claim is:

A muffler for automotive gas engines including, in combination, an elongated cool-

ing and muffling chamber having a longitudinal axis and an outlet at one end, an imperforate cylindrical engine exhaust pipe 20 extended into the other end of said chamber axially thereof, a funnel air collector extending externally of the chamber for freely admitting atmospheric air into said 25 chamber, said funnel having its discharge end tapered and extending into the muffling chamber substantially beyond the end of the engine exhaust pipe and spaced from and surrounding the discharge of said engine 30 exhaust pipe whereby the hot exhaust gas as it discharges into said cooling and muffling chamber is met with a surrounding condensed flow of cooling air.

NATHANIEL G. WARTH.
